UNITED STATES PATENT OFFICE

162,628

TOY AMPHIBIOUS MOTOR VEHICLE

Bernard Carlin, Orange, Tex., assignor of one-half to Levingston Shipbuilding Company, Orange, Tex., a corporation of Delaware

Application November 29, 1949, Serial No. 6,310

Term of patent 14 years

(Cl. D34—15)

To all whom it may concern:

Be it known that I, Bernard Carlin, a citizen of the United States of America, residing at Orange, in the county of Orange and State of Texas, have invented a new, original, and ornamental Design for a Toy Amphibious Motor Vehicle, of which the following is a specification, reference being had to the accompanying drawings, forming a part thereof.

Fig. 1 is a top plan view of the toy amphibious motor vehicle showing my design;

Fig. 2 is a side elevational view thereof;

Fig. 3 is a bottom plan view thereof;

Fig. 4 is a front elevational view thereof; and

Fig. 5 is a rear elevational view thereof.

I claim:

The ornamental design for a toy amphibious motor vehicle, as shown.

BERNARD CARLIN.
